BACK SPACING MECHANISM

James F. Koca, Woodstock, Ill., assignor to
 Woodstock Typewriter Company, Woodstock,
 Ill., a corporation of Illinois

Application March 2, 1933, Serial No. 659,336

19 Claims. (Cl. 197—91)

This invention relates to typewriters and particularly to shift mechanism for typewriters. More specifically the invention relates to mechanically operated electrically controlled back spacing mechanism for electrically operated typewriters.

The primary object of the invention is to provide new and improved back spacing mechanism for electrically operating an escapement rack 10 and consequently the carriage upon the depression of a single key lever.

Another object is to provide new and improved means for back spacing the carriage one notch upon the depression of a single key lever.

15 A further object is to provide new and improved means for back spacing the carriage continuously and intermittently one notch at a time when a single key lever is continuously depressed.

A still further object is to provide novel and improved means for preventing operation of the back spacing mechanism when the carriage has reached the end of its back space movement.

25 Still another object is to provide new and improved means operated by a driven auxiliary shaft for selectively back spacing the escapement rack and consequently the carriage one space upon the depression of a key lever, or continuously but intermittently upon depression of another key lever and providing means cooperating with said mechanism for preventing operation of the back spacing mechanism when the carriage has reached the end of its back spaced position.

Numerous other objects and advantages will be apparent throughout the progress of the following specification.

The accompanying drawings illustrate a selected embodiment of the invention and the views therein are as follows:

Fig. 1 is a transverse detail sectional view 40 through a typewriter and embodying the invention.

Fig. 2 is a detail rear elevation, parts being broken away for the sake of clearness.

Fig. 3 is a detail plan section showing some of 45 the operating mechanism.

Fig. 4 is a detail transverse sectional view showing some of the parts shown in Fig. 3 and Fig. 1.

Fig. 5 is a detail sectional view showing several 50 of the parts in Fig. 1 with the parts in partly advanced position.

Fig. 6 is a detail rear elevation partly in section.

The typewriter to which the invention refers 55 has a frame 10 which supports the front and rear

carriage rails 11 and 12 respectively supporting a carriage 13. The particular typewriter herein shown for the purpose of illustration is a "Woodstock" typewriter and, in general, includes certain parts which are standard on Woodstock machines. Various parts will not be described except those in conjunction with the various members for mechanically shifting the carriage. A drive shaft 14 is electrically driven by a belt co-operating with a pulley 15 fixed to an auxiliary 10 shaft 16. A main drive pulley 17 is also fixed to the auxiliary shaft 16 and is driven by a motor, not shown. The drive shaft 14 is for the purpose of mechanically driving the type bars in a manner well known in the art.

15 A back space key lever 18 is pivotally supported at 19 to a sub-frame 20, there being a spring 21 to urge the key lever 18 in its normal initial upward position.

20 A link 22 is pivotally connected to the key lever 18 as indicated at 23 and is operatively connected to a lever 24 as indicated at 25, Fig. 1. The lever 24 is pivoted to a shaft 26 and has an arm 27 which carries a pawl 28 which is pivoted to the arm 27 as indicated at 29. The pawl 28 has a 25 latching end 30 which is adapted to latch with a latching end 31 on a latch 32. The latch 32 is pivoted at 33 to an ear 34 which is struck out from an end bracket 35. A spring 36 is connected to the latch 32 and urges the latch 32 in a downward direction, being limited by a tail-piece 37 which is adapted for engagement with the bracket 35 as indicated at 38. The latch 32 has a locking pawl 39 which is adapted to engage a pawl 40 pivoted at 41 to a cam 42. The cam 30 35 40 45

40 The pawl 40 is revolvably mounted on the auxiliary shaft 16. The pawl 40 is provided with a locking end 43 which is adapted to engage a tooth 44 on a driving ratchet 45 which is fixed to the shaft 16 and rotates therewith. Therefore, upon depression 45 of the back space key lever 18, the link 22 will swing the arm 24 on its pivot 26, raise the pawl 28 which in turn will lift the pawl 39 out of engagement with the pawl 40. As soon as the pawl 39 is disengaged from the pawl 40, a spring 46 connected to the tail-piece 47 of the pawl 40 will cause the locking end 43 to become engaged with a tooth 44 on the ratchet 45. This engagement will cause the cam 42 to become locked to the shaft 16 and rotate therewith. The pawl 28 is provided with a tail-piece 48 which will be engaged by the pawl 40 during rotation of the cam. This engagement will move the pawl 28 to the left, Fig. 1, and allow the latch 32 to return to its original normal position where it will again 50 55

be in the path of the pawl 40 to disengage the locking end 43 from the ratchet 45 at which time the cam will cease operating.

During rotation of the cam 42, a cam follower 5 or roller 49, which rides on the peripheral surface of the cam 42, will operate a crank 50, the crank having the cam follower or roller 49 pivoted thereto. When the roller 49 is on the rise 51 of the cam 42, the crank 50 will be swung on its pivot 52 and raise its rear end 53. A link 54 is pivoted to the rear end 53 of the crank as indicated at 55. The upper end 56 of the link 54 is bent at right angles as indicated at 57 to provide an attaching ear 58. A crank 59 pivoted 10 at 60 to a part of the main frame 10 has a pivotal connection 61 with the ear 58 of the link 54. The arm 62 of the crank 59 has a pawl 63 pivoted thereto as indicated at 64. A spring 65, connected to the tail-piece 66 of the pawl 63 and to 15 an ear 67 on the crank 59, normally urges the face 68 of the tail-piece toward a stop ear 69. The pawl 63 is normally held out of engagement with the stop ear 69 and the teeth 70 of the escapement rack 71 by the end 72 of a slot 73 20 formed in a supporting plate 74, Fig. 6. However, during operation of the cam, the link 54 will be pushed upwardly, swing the crank 59 on its pivot 60 and move the pawl 63 toward the teeth 70 on the escapement rack 71. However, as 25 the cam follower advances toward the rise of the cam, the crank 59 will be given additional swinging movement causing the stop ear 69 to engage the face 68 of the pawl 63 and positively position the tooth 75 of the pawl 63 into the space between a pair of teeth 70 and move the escapement rack toward the left one space, Fig. 6. As 30 soon as the escapement rack 71 has been moved one space by the pawl 63, the face 76 of the pawl 63 will be in contact with the face 77 of the slot 73. The engagement of the face 76 with the face 77 will lock the pawl in the teeth and prevent overthrow. As soon as the pawl 63 has moved the escapement rack one notch, the cam will have made one complete revolution and the 35 pawl 40 will again have engaged the pawl 39 at which time the cam roller will return to the low spot of the cam, returning the parts to their normal initial position as shown in Fig. 1. The pawl 28 has a spring 78 fastened thereto to urge the pawl in a predetermined position. The movement of the pawl is limited by an ear 79 which is in engagement with the arm 27 of the lever 24. A spring 80, Fig. 6, is fastened to the crank 59 and assists in returning the parts. 40 Therefore, upon the single depression of the back space key lever 18, the escapement rack will only be advanced one notch, consecutive operation of the pawl 63 being prevented by the return of the pawl 39 into the path of the pawl 40 and 45 stopping further rotation of the cam with the shaft.

Where the back spacing operation is to be repeated, a repeat lever 81, Fig. 3, is provided. This repeat lever 81 is provided with a link 82, 50 Fig. 4, pivoted at 83 to a lever 84. The lever 84 is pivoted on the shaft 26, Fig. 4, and carries a pawl 85 which is pivoted at 86 to its arm 87. The pawl 85 has a latching end 88 which is adapted for engagement with the latching end 70 55 31 of the latch 32. The pawl 85 is provided with an ear 89 which engages the arm 87 to limit the pivotal movement of the pawl 85. A spring 90 is fastened to the arm 87 and to the pawl to urge the pawl 85 in a predetermined direction normally into engagement with the latching end 75

31 of the latch 32. When the repeat lever 81 is depressed, the link 82 will swing the lever 84 on its pivot 26, raise the latch 32 and cause disengagement of the pawl 39 from the pawl 40 and the cam and other parts controlled thereby will operate in the manner previously described. Continued depression of the lever 81, however, will cause continued operation of the parts to continuously and consecutively cause the pawl 36 to become engaged and disengaged from the escapement rack 71 and continuously and intermittently move the escapement rack one notch at a time. This continued operation is effected because the pawl 85 does not carry a tail-piece 48 to become engaged by the pawl 40 to return the parts to normal position. Continued depression of the repeat lever 81 keeps the latching end 39 of the latch 32 from becoming engaged with the pawl 40. Therefore, the cam will continue to rotate until the depression of the repeat lever is released.

However, if the repeat lever were depressed until the carriage reaches the end of its back spaced movement, the parts would become damaged and broken as the carriage has reached the end of its travel. Therefore, means are provided to automatically return the latch 32 into the path of the pawl 40 to prevent continued rotation of the cam irrespective of the position of the repeat lever 81. These means comprise margin stop mechanism 91 including an arm 92 pivoted to the main frame 10 as indicated at 93. The margin stop mechanism 91 is conventional with Woodstock typewriters as shown and disclosed in the copending application, Serial No. 659,332, filed concurrently herewith, and includes the slot and pin connection 94, Fig. 2, to permit slidable movement of the margin stop mechanism in the usual manner. The margin stop mechanism 91 also includes the adjustable margin stop 95 and the fixed limit stop 96 which is also shown and described in the aforesaid copending application. When either the face 97 of the marginal stop 95 or the stop 96 engages the face 98 of the marginal stop mechanism 91, 45 the arm 92 will be moved the limit of the pin and slot connection 94 as also described in the aforesaid copending application. When the arm 92 is moved by either the marginal stop 95 or the fixed stop 96, the link 99 pivoted to the arm 92 50 as indicated at 100, will move the bell-crank 101 to the left, Fig. 2. The bell-crank 101 is pivoted at 102 to the bracket 35 and has its upper end pivotally connected at 103 to the link 99, Fig. 2. The bell-crank 101 has a lower arm 104 55 formed integrally therewith which is adapted to engage an arm 105 of a bell-crank 106 which is pivoted at 107, Fig. 1, to the ear 34 of the bracket 35. The upper arm 108 of the bell-crank 106 has a formed-over portion 109, Fig. 2, terminating in an ear 110 to receive the rear ends of links 111, Fig. 1, and 112, Fig. 4. The links 111 and 112 have end slots 113, and a fastening member 114 passes through the arm 108 of the bell-crank, the slots 113 and the ear 110. The 60 links 111 and 112 are pivoted to the pawl 28 and the pawl 85 respectively by pivots 115 and 116 respectively. The movement of the arm 92 moves the link 99 and bell-crank 101 which raises the arm 105 of the bell-crank 106. The movement 65 of the bell-crank 106 moves the links 111 and 112 to the left, Figs. 1 and 4, and moves the pawls 28 and 85 out of engaging position with the latch 32. These pawls will have no effect on the latch 32 and the latch 32 will remain in the pos- 70 75 75

tion shown in Figs. 1 and 4 in engagement with the pawl 40 preventing operation of the cam. Therefore, when the carriage has reached the end of its back space travel, the pawls 39 and 40 will 5 remain in engagement even though the back space lever or the repeat lever is depressed. The ends of the links 111 and 112 are provided with slots 113 to prevent the pawl 28, when displaced by the tail-piece 48, from releasing the pawl 10 85 because the engagement of the pawl 40 with the tail-piece 48 will merely slide the link 111 the length of its slot 113 and prevent disengagement of the latching end 31 of the latch 32 with the latching ends 30 and 88 of the pawls 28 and 15 85 respectively.

A detent 117 is urged upwardly by a spring 118 and has a recess 119 which is adapted to receive a pin 120 on the cam 42 as shown in Figs. 1 and 5 to assist in holding the cam in its 20 normal initial or rest position.

Operation

When the back space lever 18 is depressed, the link 22 will swing the arm 24, and raise the 25 pawl 28 which will in turn raise the latch 36 and free the pawl 40 from the pawl 39. The spring 46 will, therefore, pull the latching end 43 of the pawl 40 into engagement with the ratchet and the cam 42 will rotate. The rotation of 30 the cam 42 will move the crank 50 and cause the link 54 to be pushed upwardly and swing the crank 49 on its pivot 60 to cause the pawl 63 to engage the teeth 70 on the escapement rack 71 and move the escapement rack one notch where 35 the escapement rack 71 will be held in its back spaced position by the usual escapement mechanism. The spring 36, during the aforementioned operation, will pull the latch into position to be engaged by the pawl 40 to stop further rotation 40 of the cam because the engagement of the pawl 40 with the pawl 39 on the latch 32 will release the latching end 43 of the pawl from the ratchet 45. As soon as the cam has completed its travel, the 45 parts will be returned to their normal initial position.

When the repeat lever 81 is depressed, the link 82 will rock the arm 84 on its pivot and cause the pawl 85 to raise the latch 32 to disengage the pawl 39 from the pawl 40. The cam is then 50 free to rotate continuously to continuously move the escapement rack one notch at a time intermittently. When, however, the carriage has reached the end of its back spaced movement, the marginal stop mechanism 91 will cause movement of the arm 92. Movement of the arm 92 will operate the bell-crank 101 which, in turn, will operate bell-crank 105 to move the links 111 and 112. Movement of the links 111 and 112 will shift the pawls 28 and 85 out of operative 55 engagement or into inoperative position relative to the latch 32. Therefore, the latch 32 will be pulled by the spring 36 into position and into locking engagement with the pawl 40 to prevent rotation of the cam with the shaft 16.

The invention provides new and improved back spacing mechanism for electrically operating an escapement rack by the depression of a single key lever, the operation of the escapement rack causing movement of the carriage. The back spacing mechanism is adapted to selectively back space one space at a time or back space the carriage successively and continuously. Parts of the mechanism for single back spacing are provided for causing the continuous back spacing 70 operation, means being provided to kick-out or 75

trip certain mechanism to prevent operation of the back spacing mechanism when the carriage has reached the end of its travel. The parts are rigidly constructed and are compactly arranged. The mechanism is relatively simple and is not 5 likely to get out of order.

Changes may be made in the form, construction, and arrangement of the parts without departing from the spirit of the invention or sacrificing any of its advantages, and the right is 10 hereby reserved to make all such changes as fairly fall within the scope of the following claims.

The invention is hereby claimed as follows:

1. Back space mechanism for typewriters comprising a key lever, a carriage, an escapement rack on the carriage, an electrically driven shaft, and operating means cooperating with the driven shaft and controlled by the key lever for operating the escapement rack for back spacing the carriage, and means for preventing operation of said operating means when the carriage is in fully back spaced position. 15

2. Back space mechanism for typewriters comprising a key lever, a carriage, an escapement rack on the carriage, operating means controlled by the key lever and cooperating with the escapement rack for back spacing the carriage successively as long as the key lever is depressed, and means for preventing operation of said means 30 when the carriage has reached the extent of its travel. 25

3. Back space mechanism for typewriters comprising a key lever, a carriage, an escapement rack on the carriage, electrically operated means 35 controlled by the key lever and cooperating with the escapement rack for back spacing the carriage one space upon depression of the key lever, a repeat back space lever, and means cooperating with the first named means and controlled 40 solely by the repeat lever for successively back spacing the carriage.

4. Back space mechanism for typewriters comprising a key lever, a carriage, an escapement rack on the carriage, operating means controlled 45 by the key lever and cooperating with the escapement rack for back spacing the carriage one space upon depression of the key lever, a repeat back space lever, means cooperating with said operating means and controlled by the repeat lever for 50 successively back spacing the carriage, and means for preventing operation of the operating means when the carriage has reached the extent of its back space travel.

5. Back space mechanism for typewriters comprising a pair of key levers, a carriage, an escapement rack carried by the carriage, means engageable with the escapement rack for back spacing the carriage, mechanism including a rotary shaft for operating the last named means, 55 and means associated with both of said levers for causing operation of said mechanism to move the carriage upon depression of either of said levers, and means for preventing operation of said mechanism to move the carriage when the latter is in fully back spaced position. 60

6. Back space mechanism for typewriters comprising a pair of key levers, a carriage, an escapement rack carried by the carriage, means engageable with the escapement rack for back spacing 70 the carriage, mechanism for operating the last named means, means selectively associated with one of said levers for causing operation of said mechanism to move the carriage one space upon depression of the last named key lever, and 75

- means selectively associated with the other key lever to back space the carriage successively and continuously upon continued depression of said other key.
5. Back space mechanism for typewriters comprising a pair of key levers, a carriage, an escapement rack carried by the carriage, means engageable with the escapement rack for back spacing the carriage, mechanism for operating the 10 last named means, means associated with one of said levers for causing operation of said mechanism to move the carriage one space upon depression of the last named key lever, means associated with the other key lever to back space the 15 carriage successively and continuously during depression of said other key, and means for preventing operation of said mechanism when the carriage has been moved to the end of its back space travel.
20. Back space mechanism comprising a rotary shaft, a ratchet fixed to the shaft and rotatable therewith, a cam freely mounted on the shaft, a key lever, a carriage, an escapement rack carried by the carriage, means adapted for cooperation with the rack and controlled by the rotation of the cam to back space the carriage, a key lever, and means controlled by the key lever when depressed to lock the cam to the ratchet for rotation with the shaft and thereby back space 25 the carriage, and means for preventing rotation of the cam when the carriage has been back spaced the extent of its travel.
9. Back space mechanism comprising a rotary auxiliary cam shaft, a ratchet fixed to the shaft 30 and rotatable therewith, a cam freely mounted on the shaft, a key lever, a carriage, an escapement rack carried by the carriage, means adapted for cooperation with the rack and controlled by the rotation of the cam to back space the carriage, a key lever, means controlled by the key lever when depressed to lock the cam to the ratchet for rotation with the shaft and thereby back space 35 the carriage, trip means for releasing the cam from the ratchet when the carriage is back spaced one space, a second key lever, and means controlled by the depression of the second lever to lock the cam to the ratchet to back space 40 the carriage repeatedly.
10. Back space mechanism comprising a rotary auxiliary cam shaft, a ratchet fixed to the shaft 45 and rotatable therewith, a cam freely mounted on the shaft, a key lever, a carriage, an escapement rack carried by the carriage, means adapted for cooperation with the rack and controlled by the rotation of the cam to back space the carriage, a key lever, means controlled by the key lever when depressed to lock the cam to the ratchet for rotation with the shaft and thereby back space 50 the carriage, trip means for releasing the cam from the ratchet when the carriage is back spaced one space, a second key lever, means controlled by the depression of the second lever to lock the cam to the ratchet to back space 55 the carriage, and means for preventing operation of the trip means during depression of the second lever.
11. Back space mechanism comprising a rotary auxiliary cam shaft, a ratchet fixed to the shaft 60 and rotatable therewith, a cam freely mounted on the shaft, a key lever, a carriage, an escapement rack carried by the carriage, means adapted for cooperation with the rack and controlled by the rotation of the cam to back space the carriage, a key lever, means controlled by the key lever when depressed to lock the cam to the ratchet for rotation with the shaft and thereby back space 65 the carriage, and means for preventing operation of the trip means during depression of the second lever.
12. In an electric typewriter having an electrically driven type bar driving shaft, the combination of an auxiliary shaft adapted to be driven simultaneously with said type shaft, a cam 70 freely mounted on the auxiliary shaft, a carriage, an escapement rack carried by the carriage, a toothed pawl adapted for engagement with the rack to back space the carriage, means for locking the cam to the auxiliary shaft to rotate therewith, 75 and means controlling the rotation of the cam to operate the pawl and move the carriage one space at a time, said last named means including a trip member conditioned by movement of the cam for disabling the locking means after a predetermined amount of cam rotation.
13. In an electric typewriter having an electrically driven type bar driving shaft, the combination of an auxiliary shaft adapted to be driven simultaneously with said type shaft, a cam 80 freely mounted on the auxiliary shaft, a carriage, an escapement rack carried by the carriage, a toothed pawl adapted for engagement with the rack to back space the carriage, means for locking the cam to the auxiliary shaft to rotate therewith, 85 and means controlling the rotation of the cam to operate the pawl and move the carriage one space at a time, said last named means including a trip member conditioned by movement of the cam for disabling the locking means after a predetermined amount of cam rotation.
14. In an electric typewriter having an electrically driven type bar driving shaft, the combination of an auxiliary shaft adapted to be driven simultaneously with said type shaft, a cam 90 freely mounted on the auxiliary shaft, a carriage, an escapement rack carried by the carriage, a toothed pawl adapted for engagement with the rack to back space the carriage, means for locking the cam to the auxiliary shaft to rotate therewith, 95 and means controlling the rotation of the cam to operate the pawl and move the carriage one space at a time, additional means controlling the operation of the cam to cause successive intermittent back spacing of the carriage, and devices for selectively causing operation of either of said two last named means.
15. In an electric typewriter having an electrically driven type bar driving shaft, the combination of an auxiliary shaft adapted to be driven simultaneously with said type shaft, a cam 100 freely mounted on the auxiliary shaft, a carriage, an escapement rack carried by the carriage, a toothed pawl adapted for engagement with the rack to back space the carriage, means for locking the cam to the auxiliary shaft to rotate therewith, 105 and means controlling the rotation of the cam to operate the pawl and move the carriage one space at a time, additional means controlling the operation of the cam to cause successive intermittent back spacing of the carriage, devices for selectively causing operation of either of said two last named means, and means controlled by the position of the carriage to prevent operation of both of said two last named means upon operation of either or both of said devices.
16. In a back space mechanism for typewriters, a carriage, a continuously operable power driven shaft, means engageable with the carriage for back spacing it, a key lever, means operated by 110

- the key lever for connecting the power shaft and the back spacing means, means automatically operable after a single operation of the back spacing means for disconnecting said means from the power shaft, a second key lever, and means operated by the second key lever for connecting the power shaft and the back spacing means for continuous and successive operation of the latter, each of said key levers being selectively and independently operable to control its operating mechanism and effect back spacing of the carriage.
17. In a back space mechanism for typewriters, a carriage, a continuously operable power driven shaft, means engageable with the carriage for back spacing it, a key lever, means operated by the key lever for connecting the power shaft and the back spacing means, and means controlled by movement of the carriage for disconnecting said connecting means when the carriage is in fully back spaced position.
18. Back space mechanism comprising a rotary shaft, a ratchet fixed to the shaft and rotatable therewith, a cam freely mounted on the shaft, a carriage, an escapement rack carried by the carriage, means adapted for cooperation with the rack and controlled by the rotation of the cam to back space the carriage, a key lever, means controlled by the key lever when depressed to lock the cam to the ratchet for rotation with the shaft and thereby cause operation of the back spacing means, trip means conditioned by rotation of the cam for releasing the cam from the ratchet when the carriage is back spaced one space, and means cooperating with the back spacing means to prevent overthrow of the carriage.
19. In a back space mechanism for typewriters, a carriage, a continuously operable power driven shaft, means engageable with the carriage for back spacing it, a pair of key levers, means operated by one of said key levers for connecting the power shaft and the back spacing means to cause said means to back space the carriage one space, and means operated by the other of said key levers for connecting the power shaft to the back spacing means to cause said means to back space the carriage a plurality of spaces, each of said key levers being selectively and independently operable.

JAMES F. KOCA.
